METAL WORKING MACHINE

Arthur F. Hanson, Philadelphia, Pa., assignor to
 Budd Wheel Company, Philadelphia, Pa., a corporation of Pennsylvania

Application April 22, 1932, Serial No. 606,774

10 Claims. (Cl. 219—4)

This invention relates to metal working machines and more particularly to an actuating mechanism therefore having for its principal object the construction of a machine and mechanism which will enable very accurate control of the die movement during the working operation, and which will allow a very large relative movement of the dies during the loading and unloading operations of the machine independently of the cam controlling surface used during the working operation. Another object of my invention is to construct a cam which will be relatively inexpensive to make.

I attain the above desirable objects and others incidental thereto by constructing a metal working machine having in combination relatively movable dies and actuating mechanism therefor including a cam arranged to control the die movement during the welding operation and to receive the follower in nested relation during the work charging and discharging part of the operations.

My invention will be better understood from the following description when considered in connection with the accompanying drawings and its scope will be pointed out in the appended claims.

In the accompanying drawings wherein like ordinals represent corresponding parts in the various figures,

Fig. 1 is a side elevation of a machine made in accordance with the teachings of my invention.

Fig. 2 is a plan view of the same machine. Fig. 3 is a skeleton view showing the relative parts of the cam mechanism and the follower means.

Fig. 4 is a section on the line 4—4 of Fig. 3.

Fig. 5 is a view taken from the right side of Fig. 3 looking to the left showing the control mechanism schematically associated with the cam and its follower.

Resulting from the construction herein disclosed I eliminate the need of expensive cams and make the machine much more compact having the associated operating parts requiring much less head room than would of necessity be required with a machine using an ordinary cam of large size.

In accordance with my invention I provide a metal working machine having a general framework including a base 10, a plurality of supporting side members 11 and an upper structure 12 generally housing and supporting the operative parts of the machine. Mounted upon the base

member 10 is the lower stationary die member or electrode 13. The electrical connections to this member are not shown as any suitable connection will serve the purposes of my machine. Upon brackets 14 suitably mounted upon the base member 10 and properly located with respect to the dies are a plurality of pneumatically operated mechanisms 15 controlling the members 16 which are positioned between the individual work pieces, supporting them in separated relation by means of yielding resistance. This mechanism is covered by other patent applications and is only incidental to the present disclosure, consequently a further discussion thereof is deemed unnecessary. It will be apparent, however, that these instrumentalities are necessarily coordinated with the operations of the dies. Slidably mounted in the guide-ways 17 of the vertical frame members 11 is an upper platen 18 adapted to have secured to the lower face thereof the upper die or electrode 19. The member 19 is necessarily insulated from the platen and connected to a proper source of power. By means of the mechanism so far described it is obvious that relative motion between the upper and lower dies may be obtained.

The primary raising and lowering operations of the platen 18 are obtained by means of a plurality of pneumatically operated mechanisms 20 mounted at the top of the machine upon the cross structures 12. Internally of these cylinders are arranged pistons 21 connected by means of rods 22 to the shoulders 23 upon the platen. The raising and lowering of the platen is attained through this mechanism by means of control valves and air-lines, not shown. Raising motion is attained by introducing air in the lower part of the cylinder forcing the pistons upward whereas lowering movement is accomplished by exhausting the cylinder. It is obvious that these same members may be used as a buffer or shock absorber to position the die in its lowered initial working position by merely retaining in the cylinders a sufficient quantity of air to accomplish this result.

To accurately control the die movements during the loading and unloading operations of the machine as well as during the welding operations additional mechanism is required including a cam to be later described. This mechanism comprises essentially the cam 24 mounted upon the shaft 25 which is secured to the upper frame member 12 by means of suitable brackets 26. To accomplish the rotary motion of shaft 25 a source of power, for example, an electric motor 110

30 is used. The motor drives a reducing gear located within the gear housing 27 by means of a chain drive 28. The reducing gear is externally associated with the pinion 29 meshing 5 with the large gear wheel 31 upon the shaft 25. The drive to the shaft 25 from the motor 30 is through the chain drive 28, the gear reducing mechanism in the housing 27 to pinion 29 and thence through the large gear wheel 31. To 10 accurately control this drive it is necessary to have associated with the driving motor an electro-magnetic brake mounted upon the top of the machine and coacting with the motor by means of a brake drum 32. This mechanism 15 generally indicated at A is of the type commonly used for this purpose.

The previously described parts of the machine and the operation thereof co-operate to enable the presently described cam mechanism 20 to properly function. Cam 24, as shown in Fig. 4, has a removable surface 33 which is the active or controlling surface of the cam. The particular construction illustrated comprises a short circumferential portion 34 generally considered 25 the initial take-up to position the work parts just precedent to beginning the flash. The remainder of the cam surface up to the point 35 has a gradual increase in taper which allows the parts to approach gradually continuously and in 30 a pre-determined manner so as to burn away the adjacent surfaces preparatory to the push-up which occurs at point 35 immediately before cutting off the power. The upper die 19 is actuated by means of a follower member 38 including a roller 39 adapted to engage the surface 35 of the cam 33.

The cylindrical portion 36 of the cam has a slot 37, as shown, having a depth considerably 40 in excess of the maximum cam radius and closely approximating in width the cylindrical diameter of the follower. I can raise the die 19 a relatively great vertical distance away from the lower die by allowing the follower means including the member 38 carrying the roller 39 to 45 nest within the slot during the inactive period of the machine. After the machine has been loaded and the elemental parts have been placed between the dies, the pneumatic control means are caused to operate, lowering the die by means 50 of the co-acting piston rods and platen into position. The follower is now positioned immediately below the cam preparatory to the welding operation. In this position the machine may be safely started and the welding operation begun. At the end of the sequence of motions obtained by the cam, the member 38 is again 55 raised within the slot 37 allowing the work to be removed. It is readily apparent that by means of the cam herein described a very accurate 60 welding operation may be performed by means of the cam surface and a very large vertical movement of the die can be obtained due to the nesting relation of the follower within the slot. To accomplish this same desirable result with 65 ordinary construction it would be necessary to have a cam of extremely large dimensions possibly as much as four feet in diameter. It is obvious that such a cam would be extremely expensive. The present construction allows a 70 relative vertical movement of approximately 20 inches with a cam of possibly not more than two feet in diameter.

At the right hand end of the shaft 25, as seen in Fig. 3, is a member 40 suitable for carrying 75 a plurality of contacting control elements 41

and 42, visible in Fig. 5, for operating the various switches. The push button switch 43 is used to initiate the rotary movement of the cam thru the motor 30, the circuit thereof being continued after the hand operated initiation thereof by means of the switch 44 which is freed from the eccentric member 41. The power associated with the dies for the flash welding is controlled by means of suitable switch 45 likewise associated with an eccentric cam member 42.

In the nature of safety measures operative 80 during the action of this machine, a switch 46 is connected by means of a roller and bell-crank 48 and 49 for association with a member 50 mounted upon the ram 38. As long as the ram 38 is in its raised position the switch 46 cannot close. This switch controls the main power source and consequently the machine must remain inoperative as long as the switch is open. After the machine has been loaded and the ram 90 has been lowered, the switch 46 closes and the machine operation may thus be initiated. Should the machine begin operation when some rigid structure is between the die faces, some 95 part of the same would necessarily break. To avoid this danger a steel washer 51 is mounted between two co-acting collars 52 and 53. When the load exerted upon the washer exceeds the shearing stress of the member this joint gives way and the cam surfaces are not damaged. 100 In this manner relatively inexpensive parts of the machine may be replaced without any possible destruction of the expensive dies or cam surface.

My machine is readily adaptable for quantity 110 production and therein finds its most acceptable use. The embodiment of the invention herein described and illustrated has been selected for the purpose of clearly setting forth the principles involved. It will be apparent, however, that 115 the invention is susceptible of being modified to meet the different conditions encountered in its use and I therefore aim to cover by the appended claims all modifications within the true spirit and scope of this invention.

I claim as my invention:

1. In an electric flash welding machine, dies having a degree of approach toward and recession from each other measured by those movements required for proper functioning of the 125 dies in carrying out the welding operation per se, a cam arranged to control said die movement and having a peripheral contour designed to afford such movement only, and means carried by said cam but independent of the periphery 130 thereof arranged to afford a relative die movement from and toward each other relatively much greater than the said degree of movement required to carry out the welding function per se.

2. A metal working machine having in combination, relatively movable dies and actuating mechanism therefore including a cam arranged to control the die movement during the working operation and a slot in said cam arranged to 140 receive a follower in nested relation during the work charging or discharging operations.

3. In a metal welding machine, the combination of relatively movable welding dies, power means including a ram for supplying predetermined pressure to a die during the welding operation and a cam for imparting working movement to said ram, control means operated by said ram in inactive position to prevent operation of the machine, a hand operated switch to 145

- initiate machine operation and a plurality of switches associated with said cam, one to continue machine operation after the initiation thereof and one to control the welding circuit 5 in synchronism with the die movement.
4. In an electric flash welding machine, dies having a degree of approach toward and recession from each other measured by those movements required for proper functioning of 10 the dies in carrying out the welding operation per se, a cam controlling this movement and having a peripheral contour designed to afford such movement only, and means including a slot independent of said periphery to afford a 15 relative die movement from and toward each other relatively much greater than the said degree of movement required to carry out the welding function per se.
5. In a metal working machine, the combination of, relatively movable dies, a cam for imparting predetermined movement to said dies and having a diametral slot, follower means arranged to transfer the cam motion to a die, and means arranged to position said follower means 20 in operative relation to the cam surface or nested 25 interiorly of said slot.
6. In an electric flash welding machine, dies having a degree of approach toward and recession from each other measured by those 30 movements required for proper functioning of the dies in carrying out the welding operation per se, a cam controlling this movement having a peripheral contour designed to afford such movement only, and a diametral slot therein 35 independent of said periphery arranged to afford a relative die movement from and toward each other relatively much greater than the said degree of movement required to carry out the welding function per se.
- 40 7. A machine adapted to butt weld together the cross sectional parts of members of hollow
- cross section, comprising relatively movable welding dies, means arranged to position one of said dies into relative working position, means arranged to control the die movement during the working operation and independent means co-operative therewith arranged to provide relatively much greater relative die movement than the degree of die movement requisite during the working operation.
8. A metal working machine having, in combination, relatively movable dies and actuating mechanism therefor including a cam arranged to control the relative die movement during the metal working operation per se, a follower arranged to transfer the cam contour motion to said dies, said cam having a diametral slot of a depth at least so great as the maximum cam radius, and arranged to receive said follower in nested relation thereto during the work charging or discharging operations.
9. In a metal working machine, the combination of relatively movable dies, a cam for imparting pre-determined movement to said dies and having a diametral slot, follower means arranged to transfer said cam motion to said die, 100 means arranged to position said follower in operative relation to said cam surface or nested interiorly of said slot, and means interconnecting said follower means and said die, and arranged to pre-determine the load transmitted 105 through the intermediation of said follower means.
10. In a metal working machine having relatively movable dies, a cam arranged to control said dies during a portion of their relative movement, and means independent of the periphery of said cam providing a relative movement of said dies greater than the maximum radius of said cam surface.
